CARD GAME ACCESSORY

Arthur W. Carlson, Marquette, Kans., assignor
of one-half to Ernest Johnson, Marquette,
Kans.

Application May 22, 1939, Serial No. 275,079

1 Claim. (Cl. 273—148)

The present invention relates to new and useful improvements in card game accessories and has for one of its important objects to provide, in a manner as hereinafter set forth, a device of this character comprising means for holding a score pad for convenient use.

Another very important object of the invention is to provide an accessory of the character described comprising a container for the reception of a deck of cards, said container including novel means for facilitating the removal of said cards.

Still another important object of the invention is to provide a card game accessory of the aforementioned character comprising means for holding a removable ash tray in position for convenient use.

Other objects of the invention are to provide a card game accessory of the character set forth which will be comparatively simple in construction, strong, durable, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a card game accessory constructed in accordance with the present invention.

Figure 2 is a view in vertical longitudinal section through the device, taken substantially on the line 2—2 of Fig. 1.

Figure 3 is a cross sectional view, taken substantially on the line 3—3 of Fig. 1.

Figure 4 is a view in side elevation of the device, a portion thereof being broken away in section, the cover for the card receptacle being shown in raised position.

Figure 5 is a detail view in cross section, taken substantially on the line 5—5 of Fig. 1.

Figure 6 is a bottom plan view of the ash tray.

Figure 7 is a view in side elevation of a slightly modified form of the invention.

Referring now to the drawings in detail, it will be seen that the reference numeral 1 designates a substantially rectangular base which may be of any suitable material. A covering sheet 2 is adhesively secured to the bottom of the base 1. Mounted on one end portion of the base 1 is a receptacle 3 for the reception of a deck of cards. The receptacle 3 includes a hinged cover 4.

Mounted in the receptacle 3 is a follower 5 in the form of a plate of suitable material which is adapted to support a deck of cards. One end of the follower 5 is suspended in elevated position from the cover 4 through the medium of hangers 6. The other end of the follower 5 rests on the base 1 and terminates in an upwardly extending, curved retaining flange 7. This is illustrated to advantage in Fig. 2 of the drawings.

Mounted on the cover 4 of the receptacle 3 is a substantially rectangular metallic plate 8. Rigidly secured on the plate 8 is a substantially U-shaped upper plate 9 having raised inner marginal portions 10 (see Fig. 3). The reference numeral 11 designates a removable ash tray which is adapted to be mounted on the cover 4. Toward this end, the tray 11 has secured to its bottom a metallic plate 12 including downwardly offset end portions 13 which are slidably insertable in the grooves or channels provided therefor by the raised marginal portions 10 of the plate 9. The tray 11 is provided with one or more cigarette holders 14.

Mounted on the portion of the base 1 which is free of the receptacle 3 is a pad 15. The pad 15 is secured in position by means including a bar 16 which is clamped transversely across the end portion of said pad which is adjacent the receptacle 3. The bar 16, in turn, is secured in position by bolts 17 which extend through the pad 15 and are threaded into female members 18 which are provided therefor in the base 1. This is shown in Fig. 5 of the drawings. A tube 19 is mounted horizontally on the inclined front wall 20 of the receptacle 3 for holding a pencil, as at 21.

It is thought that the manner in which the device is used will be readily apparent from a consideration of the foregoing. The cards, when in the receptacle 3, rest on the follower 5. When the cover 4 is swung upwardly to open position, as seen in Fig. 4 of the drawings, one end of the follower 5 is lifted thereby thus elevating the deck of cards in a manner to facilitate the removal thereof. The mounting of the ash tray 11 is such that it may be expeditiously removed for emptying or for any other purpose. Should it not be desired to use the ash tray 11, the receptacle 3 a suitable ornamental plate or the like (not shown) may be substituted therefor on the plates 8 and 9. The sheets comprising the score pad 15 may be conveniently torn off along one edge of the bar 16. To facilitate this, these score sheets are perforated, as at 22. Also, the score

pad 15 may be expeditiously renewed when desired by simply removing the bolts 17.

In the modification shown in Fig. 7 of the drawings, the reference numeral 23 designates a drawer for the reception of a deck of cards which is slidable laterally in the receptacle 3. A resilient sheet metal clamp 24 is mounted on the base 1 for securing the score pad 15 in position. The clamp 24 is provided with a lip 25 which engages the pad 15 and which facilitates tearing the sheets therefrom. A knob 26 is provided for opening the clamp 24 to facilitate the insertion or removal of the score pad. In other respects the modification illustrated in Fig. 7 is substantially similar in construction and operation to the form of the invention shown in Figs. 1 to 6, inclusive.

It is believed that the many advantages of a card game accessory constructed in accordance

with the present invention will be readily understood and although preferred embodiments of the device are as illustrated and described, it is to be understood that further modifications may be resorted to which will fall within the scope of the invention as claimed.

What is claimed is:

A card game accessory comprising a receptacle for the reception of a deck of cards, said receptacle including a hinged cover, a follower in the receptacle for elevating the cards when the cover is opened, said follower including a flat plate-like member having one end curving upwardly and toward the other end and a hanger connecting said other end to the cover for causing said other end to be lifted when the cover is swung upwardly with the curved end rocking on the bottom of the receptacle.

ARTHUR W. CARLSON.
